UNITED STATES PATENT OFFICE.

THOMAS E. THOMAS, OF NILES, OHIO.

BLAST-FURNACE CONSTRUCTION.

1,137,244.

Specification of Letters Patent. Patented Apr. 27, 1915.

Application filed July 17, 1913, Serial No. 779,555. Renewed September 24, 1914. Serial No. 863,383.

To all whom it may concern:

Be it known that I, THOMAS E. THOMAS, a citizen of the United States, residing at Niles, in the county of Trumbull and State 5 of Ohio, have invented a new and useful Improvement in Blast-Burnace Constructions, of which the following is a full, clear, and exact description, reference being had to the accompanying drawings, forming part 10 of this specification, in which—

Figure 1 is a vertical section of a portion of a blast furnace stack embodying my invention; Fig. 2 is a horizontal section of a portion of the stack on a larger scale; Fig. 15 3 is an elevation of one of the coolers or cooling units; and Fig. 4 is a vertical section of the same.

My invention has relation to certain new and useful improvements in blast furnace 20 construction, and is more particularly designed to provide means of novel and effective character for cooling the stack walls of a furnace.

My invention provides a cooling system 25 which may be permanently built into the stack wall of a blast furnace and which provides for constant circulation within such walls of a sufficient body of water to largely prevent its destruction or cutting away.

30 In carrying out my invention, in constructing the stack walls 2, I place therein a plurality of tiers of hollow cooling boxes or units 3, arranged one above another, and extending upwardly from the bosh to any desired height. Each of these cooling boxes 35 or units is in the form of a segment of a cylinder having a radius or curvature struck from the center of the stack. In the arrangement shown, the lower tier of units is

40 supported on the mantle plate 4, and the succeeding tiers are supported directly one upon another. Adjacent units are preferably, although not necessarily, slightly separated from each other at their adjacent edges 45 by intermediate portions 6 of the refractory material of the stack wall, as shown in Fig. 2.

Each unit is provided at its lower end with an inlet pipe connection 7 for relatively 50 cold water, and at its upper end with an outlet pipe 8 for the hot water, and I preferably also provide each unit with a wash-out pipe connection 9, at its lower portion. The inlet pipe connections are preferably extended within the lower portion of the units and these extensions are formed with a plu-

rality of discharge perforations 7a. I preferably place these cooling units about midway between the inner and outer surfaces of the stack wall, so that the units are completely inclosed within said wall. 60

It is necessary that the units shall possess some degree of elasticity, so that they may be capable of withstanding the expansion and contraction movements due to changes 65 of temperature. Thus, units consisting of cast iron boxes have been found to be wholly impracticable for the purpose, as they do not possess this requisite degree of elasticity and hence crack and break. To overcome 70 this, I employ units which are either cast from copper or from some alloy possessing toughness and elasticity; or I form the units, as shown in the drawings, from sheet metal plates. These plates are suitably welded at 75 the joints, and the front and back plates are braced and connected by means of a plurality of internal sleeves 10, which are placed around the stay bolts 11. In this manner, I am able to employ units of relatively large 80 size having the proper curvature to conform to the curvature of the stack wall, and which will, nevertheless, possess a very considerable degree of elasticity. I thus provide within the stack wall itself a very considerable 85 body of cooling water, which may be circulated through the units as rapidly as desired. Each unit has its own circulating connections, and in case any unit should fail in service, it may be filled up with a mud or 90 paste of refractory material forced into it through circulating pipes, and thus be permitted to remain in place within the stack wall. 95

I claim:

1. A blast furnace having a stack wall of refractory material, said wall having embedded therein above the bosh a water-cooled jacket comprising a plurality of box-like cooling members arranged one above another, together with means for circulating water through said members, substantially as described. 100

2. A blast furnace having a stack wall of refractory material, and provided above the bosh with a water-cooled jacket embedded therein, said jacket comprising a plurality of hollow cooling members whose inner walls are of sheet metal and possessing inherent elasticity or yield, substantially as described. 105

3. A blast furnace having at least a portion of its stack above the bosh provided

with a water-cooled jacket, incased within the refractory material, said jacket comprising a plurality of hollow box-like cooling members of segmental form arranged in vertical and horizontal tiers and providing within that portion of the stack which contains them a body of cooling water which surrounds the major part of that portion of the stack, together with means for circulating cooling water through said members, substantially as described.

4. A blast furnace having a stack wall of refractory material, said wall having embedded therein above the bosh a plurality of tiers of hollow cooling boxes, said boxes having inherent elasticity to adapt them to expansion and contraction movements of said wall, said boxes forming means for providing within said wall a relatively large body of cooling water, substantially as described.

5. A blast furnace having its stack wall above the bosh formed of an inner masonry wall, an outer masonry wall, and a hollow metal shell interposed between said walls and having water circulating connections; substantially as described.

6. A blast furnace having its stack wall above the bosh formed of an inner masonry wall, an outer masonry wall, and a hollow metal shell interposed between said walls and having water circulating connections, said shell being composed of a plurality of independent sheet metal units arranged in vertical and horizontal courses; substantially as described.

7. A blast furnace having its stack wall above the bosh formed of an inner masonry wall, an outer masonry wall, and a hollow metal sheet interposed between said walls and having water circulating connections, said shell being composed of a plurality of independent sheet metal units arranged in vertical and horizontal courses, and the two masonry walls having connecting portions extending between some of the units; substantially as described.

In testimony whereof, I have hereunto set my hand.

THOMAS E. THOMAS.
